(57) **CLAIM**

The ornamental design for a cargo radar housing as shown and described.

DESCRIPTION

FIG. 1 is a top view of the cargo radar housing in accordance with the new design;

FIG. 2 is a front view in accordance with the new design;

FIG. 3 is a bottom view in accordance with the new design;

FIG. 4 is a rear view in accordance with the new design;

FIG. 5 is a left side view in accordance with the new design;

FIG. 6 is a right side view in accordance with the new design;

FIG. 7 is a front perspective view in accordance with the new design;

FIG. 8 is a rear perspective view in accordance with the new design;

FIG. 9 is another front perspective view in accordance with the new design;

FIG. 10 is another rear perspective view in accordance with the new design;

FIG. 11 is another rear perspective view in accordance with the new design;

FIG. 12 is another rear perspective view in accordance with the new design;

FIG. 13 is a perspective view thereof in an environment of use;

FIG. 14 is a perspective view thereof in another environment of use; and,

FIG. 15 is a perspective view thereof in another environment of use.

The broken lines in the drawings depict portions of the cargo radar housing that form no part of the claimed design. The broken lines shown in FIG. 13, FIG. 14, and FIG. 15 depict environmental subject matter that forms no part of the claimed design.

1 Claim, 12 Drawing Sheets
